(57) **CLAIM**

The ornamental design for a seismic node, as shown.

DESCRIPTION

FIG. 1 is a perspective view of the seismic node according to the design

FIG. 2 is a left side view of the seismic node according to the design

FIG. 3 is a right side view of the seismic node according to the design

FIG. 4 is a top view of the seismic node according to the design; and,

FIG. 5 is a bottom view of the seismic node according to the design.
